UNITED STATES PATENT OFFICE.

JOHN EDWARD GLOEKLER, OF PITTSBURGH, PENNSYLVANIA.

SHEET-METAL SINK CONSTRUCTION.

Application filed December 10, 1926. Serial No. 153,819.

My invention consists in an improvement in sinks and similar constructions, for the purpose of providing a vessel or utensil having a continuously smooth interior surface over the interior of the several walls of such an article.

In the manufacture of sinks, tubs, and the like for kitchen or laundry use, sheet metal constructions have been utilized with side, 10 end and bottom walls joined in various ways, usually by overlapping construction, either riveted, bolted, or soldered together.

Whether the interior surfaces are left plain, or are finished by application of 15 enamel or otherwise, the overlapping edges effect a more or less abrupt interruption to the smooth interior surface, with crevices, small pockets, and other objectionable variations, tending to collect foreign matter and 20 preventing the easy cleaning of the interior.

In my improved construction, I avoid these objections by so constructing the walls and their joined portions by an interfitting continuous surface welded connection between 25 the meeting edges at various points so as to provide continuous flush surfaces throughout, with an avoidance of the objections above noted.

One preferred embodiment of the invention is illustrated in the accompanying drawings, in which:

Fig. 1 is a perspective view of the body portion of a sink constructed in accordance therewith;

35 Fig. 2 is a plan view of Fig. 1;

Fig. 3 is a vertical cross section on the line III—III of Fig. 1;

Fig. 4 is a vertical section on the line IV—40 IV of Fig. 1, transverse thereto;

Fig. 5 is a horizontal cross section on the line V—V of Fig. 3;

Fig. 6 is an enlarged sectional detail view, showing the corner construction, on the line VI—VI of Fig. 1;

45 Fig. 7 is a similar sectional view on the line VII—VII of Fig. 6; and

Fig. 8 is a detail view showing the cut-out portion of the rear wall for interfitting connection with the side wall, in forming 50 such corner connection.

The sink as a whole, in the form shown,

is formed of a continuous sheet or blank of sheet metal, bent to provide the rear wall 2, bottom 3, and front wall 4, the corner bends 5 being rounded, as shown, to provide continuous integral construction. 55

Rear wall 2 is extended upwardly to provide the usual back 6 for mounting of the faucets or other fittings, and is turned backwardly at the top and sides by flanges 7 and 8. 60 Such back portion extends to any desired height and is of the extreme outer width of the main sink body portion, including its rounded edges. Such edges, at the front, as shown in Fig. 1, are formed by turning the metal outwardly and downwardly, as clearly shown, providing a substantially half round rim 9, and such rim extends across the front upper edge of the sink as an integral portion of the continuous wall plate 2—3—4. 65

The sides 10 of the sink are made of separate sheet metal blanks, pressed in suitable dies to form inwardly turned rounded lower corner portions 11 and outwardly and downwardly turned rounded upper edge portions 12, at each side. The latter correspond in size and are on the same general plane as the front rim 9, so as to effect a continuous rim from the side edge portion of the back at one side, along the front, and then back 70 along the other side to the opposite side edge portion of the back, as clearly shown in Fig. 1. 75

The corner portions of side 10 are cupped in the pressing operation, so as to provide 85 easily rounded corners, which merge into the plane of the side, bottom, front and back walls, when the blanks are assembled and finally joined, as hereinafter described.

The inwardly turned edges of sides 10, at 90 the front, bottom, and back, terminate in edges which meet the side edges of the main blank 2—3—4 on the welding line α . Such line, at each side of the construction, provides a meeting and welding joint on the 95 continuous plane α — α , Fig. 4, defining a generally U-shaped form of joint.

The back wall 6 is cut out, as indicated at 13, for joint connection with the rear edge of the upper rounded rim 12, and the side edge portions of the back 2 are also cut out, as at 14, to a distance equalling the inward 100

projection of the rounded corner portions 15 of the sides 10. By such construction, the sides, when placed in position, interfit throughout with the main front, bottom and back portions, and are flush therewith at every point.

The meeting edges, as thus brought together, are then electrically welded continuously along the line *a*, from the front, along 10 the bottom and clear to the back, so that the sides as thus joined are, in effect, flush continuations of such portions. The corners of the rounded rims 9 and 12 are similarly joined and welded, as at 16, the corner terminals being provided with a miter face for such purpose, as shown.

At the inner rear upper corner portions of each side connection, immediately below the juncture of the rounded edge 12 20 with the back, there is formed a small angular pocket, due to the upper edge terminal of the inner rounded fillet formation of the corner 15, as at 17. Such corner is preferably filled with solder or other suitable material, so as to avoid any projecting edges 25 and give a neatly rounded concave joined surface.

As thus connected, there is a substantially 30 integral juncture between the several walls forming the basin or body portion of the sink, and its parts. Any projections or roughness along the welded seam *a* may be ground off or otherwise removed so as to render the interior surface smooth, after 35 which it may be covered with any suitable coating material, as an enamel finish, or tin coating, or hot galvanized treatment.

The vessel may, however, be left unfinished, and will still maintain its advantages, due to the manner of construction, 40 if it is desired to use it without any finish whatever.

For the purpose of heating the sink or its contents, as for cleaning or other purposes, 45 I provide a burner 20 of any suitable construction, provided with a gas supply pipe 21, to effect combustion immediately under the sink bottom.

A surrounding downwardly extending coping or apron 22 of sheet metal, preferably 50 perforated, surrounds the burner, protecting it from draft, and enclosing the combustion chamber, as clearly shown in Figs. 3 and 4.

55 The various advantages of the invention will be readily understood and appreciated by all those familiar with this class of construction. It is provided with any suitable or desired fittings, waste water connection, 60 supporting legs, etc., and may, of course, be made in different sizes or designs, but all such changes are to be understood as within the province of the skilled mechanic and the scope of the following claims.

65 What I claim is:

1. In the construction of sheet metal sinks and the like, a continuous blank forming a back, bottom and front wall, cut out at the back for abutting connection with the side walls, and side walls having inwardly turned edges and outwardly turned 7 rims welded thereto.

2. In the construction of sheet metal sinks and the like, a continuous blank bent upon 75 itself to form a back, bottom and front wall and cut out at each side of the back for abutting connection with the side walls, and side walls having rounded corner portions bent inwardly with their inner vertical edges in abutting engagement with the edges 80 of said blank forming fillet portions and welded thereto, and outwardly turned rim portions.

3. In the construction of sheet metal sinks and the like, a continuous blank bent 85 upon itself to form an upwardly extending flat faced back, a bottom, and a front wall having an outwardly rounded top rim portion with chamfered corners, and side walls having rounded corner portions bent 90 inwardly with their edges in abutting engagement with the edges of the front, bottom and back portions and welded thereto.

4. In the construction of sheet metal sinks and the like, a continuous blank bent upon 95 itself to form an upwardly extending flat faced back, a bottom, and a front wall having an outwardly rounded top rim portion with chamfered corners, and side walls having rounded corner portions bent 100 inwardly with their edges in abutting engagement with the edges of the front, bottom and back portions and welded thereto, the front wall and side wall portions having outwardly turned rims welded at 105 their meeting edges.

5. In the construction of sheet metal sinks and the like, a continuous blank bent upon 110 itself to form an upwardly extending flat faced back, a bottom, and a front wall having an outwardly rounded top rim portion with chamfered corners, and side walls having rounded corner portions bent inwardly 115 with their edges in abutting engagement with the edges of the front, bottom and back portions and welded thereto, the rear wall portions being cut out to conform to the rim portions of the sides and welded thereto.

6. In sheet metal sink construction, the combination with a sheet metal back having cut out clearance openings at its side edge portion, of a side wall member having an inwardly turned rear edge portion and an outwardly turned rim in abutting engagement therewith and electrically welded thereto.

7. In sheet metal sink construction, the combination of a pressed sheet metal blank having an upper backwardly flanged 130

splash board, a main back wall portion integral therewith having cut out clearance portions for the side edge and rim portions, a bottom wall member forming a bent extension of the back and a front wall member forming a bent extension of the bottom having an upper outwardly turned rim, and

similar side wall members having rounded corner portions and a rounded rim welded to and forming flush continuations of said members. 10

In testimony whereof I hereunto affix my signature.

JOHN EDWARD GLOEKLER.
